AERIAL MERRY-GO-ROUND

Lee U. Eyerly, Salem, Oreg.

Application January 17, 1941, Serial No. 374,886

6 Claims. (Cl. 272—40)

This invention relates generally to amusement devices and particularly to an aerial merry-go-round.

The main object of this invention is to construct an amusement device of the merry-go-round type in which the passenger-carrying elements are in the form of aeroplanes which are partially under the control of the occupants.

The second object of this invention is to construct a merry-go-round of the class described wherein the aerial cars may be maneuvered while in motion, but are forced to "level off" when nearing the ground.

The third object of this invention is to construct a merry-go-round of the class described which will provide unique thrills for the riders without subjecting them to unnecessary hazards.

These and other objects are accomplished in the manner set forth in the following specification as illustrated in the accompanying drawings, in which:

Fig. 1 is a plan of the ride.

Fig. 2 is an enlarged view of one of the planes.

Fig. 3 is a fragmentary section taken along the line 3—3 of Fig. 5.

Fig. 4 is a fragmentary vertical section showing the parts in a landed position.

Fig. 5 is a view similar to Fig. 4, but showing the parts in a flying position.

Fig. 6 is a fragmentary vertical section showing a modified form of the device.

Fig. 7 is a plan of Fig. 6.

Fig. 8 is a fragmentary section taken along the line 8—8 in Fig. 6.

Fig. 9 is a fragmentary section through a modified form of the device showing a plane in a landed position.

Fig. 10 is a plan of Fig. 9.

Fig. 11 is a view similar to Fig. 9 showing the plane in a flying position and executing a "roll."

Fig. 12 is a fragmentary section taken along the line 12—12 in Fig. 9.

Similar numerals refer to similar parts throughout the several views.

Referring in detail to the device shown in Figs. 1 to 5, inclusive, there is shown a base 10 upon which is mounted a vertical thrust bearing 11 upon which journals the lower end 12 of the revolvable spindle 13 on whose upper end is secured a cable winding drum 14. Around the end 12 is formed a gear 15 which meshes with the pinion 16 of the driving motor 17 which may be controlled in any suitable manner, not shown.

The spindle 13 is revolvable within the sleeve 18, whose lower end 19 is flanged and supported

by the anti-friction bearings 20 upon the end 12. Radial anti-friction bearings 21 maintain the relationship between the spindle 13 and the upper end of the sleeve 18. The sleeve 18 is supported by the anti-friction radial thrust bearings 22 within the head 23 which is supported by the standards 24 which in turn are supported by the base 10. Suitable braces 25 are provided to insure the necessary rigidity for the structure.

From the sleeve 18 are formed a plurality of ears 26 to each of which is attached, by means of a bolt 27, the foot of a fixed arm 28 whose upper portion 29 is outturned and has attached to its outer end 30 a short cable 31, the purpose of which will be explained later.

The arms 28 are held from pivoting downwardly about the bolt 27 by means of the horizontal cables 32 which are secured to the arms 28 and the flange 33 at the upper end of the sleeve 18.

Hinged to each arm 28, by means of a bolt 34, is a boom arm 35 which is in the form of a bell crank lever whose end 36 has secured thereto a grooved cable-supporting block 37. A cable 38, which is secured to the boom 35 at the eye 39, passes over the grooved block 37 and has its end 40 secured to the drum 14.

It is desirable to provide a spring 41 in the cable 38 in order to make the car responsive to a limited controlling action on the part of its operator. A car unit consists of a fuselage 42 which is shown rotatably mounted on its forward end 43 only. From the end 43 projects the spindle 44 which is mounted in the anti-friction bearings 45 disposed within the boom end 46.

On the outer end of each spindle 44 is secured a crank arm 47 on whose pin 48 is rotatably mounted the cable fastening 49 to which is attached one end of a cable 31. The fuselage 42 is provided with the usual wings 50, ailerons 51, elevators 52, and rudder 53. The members 51, 52, 53 are provided with the usual controls, not shown, it being understood, of course, that the operator's ability to control the movement of his plane is limited by the resiliency of the spring 41.

It is also desirable to provide a landing gear 54, the purpose of which is to support the ship firmly when it is on the ground.

The operation of the device is as follows:

Assuming that the passengers are within the plane, which is in the position shown in Fig. 4, it will first be noted that when the landing gear 54 engages the ground, that the cable 31 is taut; that is, the crank 47 assumes a straight line position in which it points toward the block 37.

The purpose of this construction is to prevent

the making of a landing when the wings 50 are not in a horizontal position.

With the passengers on board, the motor 17 is operated, causing the spindle 13 to revolve and the cable 40 to be wound upon the drum 14 causing a lift to be exerted against the bell crank lever of the boom 35; and the fuselage 42 to be lifted in an arcuate path, of which the bolt 34 forms the center, the direction of lift being indicated by the dotted line 55.

It can be seen that as the fuselage 42 rises, its resistance to a lifting action increases to a point where a resultant of the forces causes a rotating movement to be imparted to the sleeve 18 and the attached parts, causing the various units 42 to revolve in circular orbits.

Owing to the presence of a spring 41 in each cable 38, it follows that a fuselage 42 may be raised or lowered with relation to the other planes by the use of its own ailerons 51 and elevators 52. It will be noted that although ailerons and elevators are employed, those on the same side of the aeroplane will naturally work in the same direction at the same time, instead of oppositely, as is the normal practice, owing to the fact that the aeroplanes in this device will always operate on a level longitudinal axis. That is to say, if it is desired to roll the fuselage clockwise, then the right hand aileron and elevator vanes are raised, and the left hand ailerons and elevators are lowered. Actually, the members 52 under such conditions do not serve as elevators at all, but are actually ailerons disposed at the rear end of the plane.

In the form of the device shown in Figs. 6 to 8 inclusive, there is provided a base 70 upon which is mounted a vertical thrust bearing 71 whose anti-friction ball bearings 72 support a gear 73 which meshes with a pinion 74 of the operating motor 75. The motor 75 is supported on the frame 76 upon whose upper end is mounted the revolvable turret 77 which is supported upon the frame 76 by means of the anti-friction bearings 78.

A vertical spindle 79 is secured to the turret 77 and gear 73 by means of the keys 80 and 81.

In the form of the device shown in Figs. 6 to 8 inclusive, there is shown a fuselage 82 having the usual wings 83, ailerons 84 and elevators 85 under the control of the operator by means similar to those now in common use, except that the ailerons 84 and elevators 85 act in the same direction simultaneously, instead of as is the normal case. The usual landing gear 86 is also indicated. The fuselage 82 is mounted along its longitudinal axis on trunnions 87 and 88 which journal in the bearings 89 and 90.

The bearings 89 and 90 are secured by the cables 91 to the yoke 92 whose strap 93 passes through a hole 94 in the arm 95, whose lower end is secured to the turret 77 by means of a bolt 96, and whose upper end is held against outward movement by means of the radial brace wires 97 and circumferentially by means of the tie 97—A.

In this form of the device, the trunnions 87 have secured thereto a crank 99 to whose crank pin 100 is attached a cable fastening device 101 to which is secured a cable 102 whose opposite end is secured to the ring 103 at the upper end of the arm 95. A spring 104 is provided on the cable 102 for the purpose of taking up the slack therein and to prevent a whipping of the cable 102 as the fuselage 82 revolves on its axis.

In the form of the device shown in Figs. 9 to 75

12 inclusive, each fixed arm 130 is secured at its lower end 131 to the ears 26 and is held in position by the brace cable 32 which is attached to the flange 33.

5 5 Mounted on the upper end 132 of each arm 130 is a bell crank lever 133 comprised of a boom arm 134 and an operating arm 135. The lever 133 is rockably mounted on the bolt 136. The pulley 137 is mounted on the upper end of the arm 135.

10 15 On the outermost end of each boom arm 134 is disposed the rotatable shaft 138 on one end of which is fixed a fuselage 42 and on the other end of which is secured a crank 139 to which is connected a winding cable 140 which passes through the tube 141 to the interior of the boom arm 134 and thence over the pulley 137 and thence fastening on the flange 142 of the cable winding drum 143.

20 25 The position of the crank 139 is such that when the fuselage 42 is in a lowermost position, as shown in Fig. 9, the crank 139 will be in direct alignment with the tube 141, and that any winding action imparted by the drum 143 will cause the cable 140 to exert a lifting action at the outer end of the boom 134, and at the same time preventing the plane from being banked or rolled by the use of the ailerons 51.

20 30 In addition to the cable 140, there is provided a lifting cable 144 which is attached to the cable 140 by means of a clamp 145 and to an intermediate portion of the arm 135 by means of a pin 146.

35 40 It will be noted in Fig. 9 that the cable 144 is slack while the cable 140 is taut, whereas in Fig. 11 the conditions are reversed and the lifting action is done entirely by the cable 144, while the cable 140 is slack, permitting the plane to be rolled.

45 50 In this form of the device no attempt is made to enable the operator of the plane to vary its elevation. Its operation is otherwise identical with the previously described form of the device.

55 60 The forms of the device shown in Figs. 6 to 12 inclusive, although differing somewhat from that shown in Figs. 1 to 5 inclusive, are almost identical in their operation and in the thrills which will be experienced by the passengers as a result of riding in the same.

65 70 While I have thus illustrated and described my invention, it must be understood that I do not intend to be limited to the precise form illustrated herein. It is therefore my intention to cover all such forms and modifications thereof as fall fairly within the appended claims.

I claim:

1. A device of the class described comprising a merry-go-round having a plurality of aeroplanes adapted to be driven in a circular orbit, said planes being mounted to revolve on their longitudinal axes, means controllable from within each plane for causing said plane to revolve on its axis in response to the will of the operator, means for causing the planes to rise from the ground, and means for holding said planes upright and against revolving on their axes while near the ground.

holding said planes upright on their axes while nearing the ground.

3. In a device of the class described, the combination of a revolvable vertical spindle having a cable-winding drum secured thereon, a sleeve surrounding said spindle having fixed arms radiating therefrom, each of said arms having a boom hinged on the outer end thereof, a cable wound on said drum operatively connected to said boom in a manner to raise or lower same, an aeroplane having a horizontally fixed longitudinal axis attached to said boom, and means for holding said aeroplane upright and against rotation on its axis while nearing the ground, consisting of a crank secured to said aeroplane and a cable attached to said crank and to said drum wound cable whereby said crank will be held against rotation when said boom is in a lowered position.

4. A merry-go-round of the class described characterized by having a plurality of aeroplane units capable of traveling about a vertical axis at selective elevations, means for permitting said planes to revolve on their longitudinal axes at higher elevations and means for preventing the revolvement of said planes at lower flying elevations.

5. A merry-go-round of the class described having in combination a revolvable vertical

spindle, a prime mover for revolving said spindle, a cable-winding drum secured to the spindle, a revolvable sleeve disposed around said spindle constituting a support for a plurality of radial arms, a bell crank boom arm hinged to each radial arm, an aeroplane mounted on the outer end of each boom arm, each of which is revolvable on its longitudinal axis while clear of the ground, a crank attached to each of said airplanes, a winding cable attached to said cable-winding drum passing over a sheave on said bell crank lever and attached to a crank on the axis of said aeroplane in a manner to control the vertical positioning of same, and a lifting cable attached to said winding cable and to said bell crank lever whereby the aeroplane unit may be held free of the ground but permitted to rotate on its axis.

6. A merry-go-round of the class described having in combination a central driving mast, a plurality of aeroplane units, each of which is revolvable on its own longitudinal axis and all of which have means for supporting same around said mast, means for holding said planes against revolving on their axes while flying near the ground, and means for selectively causing said planes to revolve on their axes while clear of the ground.

LEE U. EYERLY.
